UNITED STATES PATENT OFFICE.

FRANK McMANUS, OF SOUTH NORFOLK, VIRGINIA.

CLOTHES-LINE SUPPORT.

No. 820,815.

Specification of Letters Patent.

Patented May 15, 1906.

Application filed May 12, 1905. Serial No. 260,089.

To all whom it may concern:

Be it known that I, FRANK McMANUS, a citizen of the United States, residing in South Norfolk, in the county of Norfolk, in the State of Virginia, have invented a certain new and useful Improvement in Clothes-Line Supports; of which the following is a specification.

I provide for conveniently arranging the clothes on the line while the line is low and for raising the whole after the clothes have been properly hung. The lines may be lowered again before taking off the clothes.

I will show and describe the device as carried out, with many returns of a single line back and forward and as having such returns extended between two of my supports; but the invention may be used with a less number of returns and even with one end of each stretch or return held stationary and one end only of the series raised and lowered.

The following is a description of what I consider the best means for carrying out the invention.

The accompanying drawings form a part of this specification.

Figure 1 is a plan view showing the invention in condition for use. There are in this figure two of my supports arranged to face each other with an ordinary clothes-line stretched back and forward between them. The remaining figures are on a larger scale. Fig. 2 is a central vertical section on a line 2 2 in Fig. 3 with the extreme upper portion in elevation. Fig. 3 is mainly an elevation at right angles to the view in Fig. 2. Fig. 4 is a section of a portion corresponding to Fig. 2, but showing a modification. Fig. 5 is a plan view of the U-shaped yoke detached; and Fig. 6 is a central vertical section of the base portion, showing a modification.

Similar letters of reference indicate corresponding parts in all the figures where they appear.

A is an upright tube. It may be made of various materials, including wood, but I will describe it as galvanized iron. A' is a foot tapered or otherwise strongly fixed thereon. A² A³ are straps cast or otherwise set in the foot and arranged in four sets extending radially to allow the horizontal bars A⁴ of wood or other suitable material to be inserted and removed at will. A⁵ represents pins inserted through holes in the straps A³, engaging in corresponding holes in the bars A⁴ to secure the arms and release them at will and

enable them to be withdrawn before housing or otherwise putting the support out of the way. The other tube A is similar and is held at the required distance in a reversed position.

Near the top of the hollow post A is a U-shaped bracket B, secured by screws C C, which screws also perform another important function, as will later on appear. On the two arms of the bracket B is mounted a shaft D, on which is secured an operating-crank D' and a spur gear-wheel D". This shaft is arranged with the gear-wheel revolving in a slot in the post A and acting upon an upright piece loosely inclosed by and vertically sliding in said post, which I will for brevity designate as the "pole" M. It is equipped with a series of teeth constituting a rack M', extending up and down on one side, arranged to be engaged by the teeth of the wheel D". The pole is raised and lowered thereby and is prevented from turning horizontally by receiving the inner ends of the screws C and also a small wheel P in a longitudinal groove m, extending the main portion of the length. The groove terminates sufficiently above the bottom to provide a stop, so that the slide M can never be entirely drawn out and lost.

P is an antifriction-wheel mounted on a pivot on the upper portion of the tube A. It runs in the groove m and performs two functions—one to contribute to resist any tendency of the upright pole to be revolved and another to reduce friction under the severe pull to which it is subjected on being raised or lowered when the lines are loaded with clothes.

M² is a transverse bar supported in the head carried on the upper end of the pole M.

In the use of the invention two of my supports will usually be employed, and I will describe them as set a proper distance apart and with their transverse bars M² approximately parallel.

W is a clothes-line tied or secured to one end of a transverse bar and extending across the space to the corresponding bar of the opposite support, where it passes partially around two of the fastenings M⁴, and thence back again, engaging two of the corresponding fastenings on the first bar, and thus extends backward and forward until the whole is made available, securing the terminal end in any ordinary or suitable manner.

To operate, if the poles are not already down the cranks are turned to lower the

poles and their attachments, and the clothes are applied and secured by clothes-pins in the ordinary manner, taking care to first fill the inner stretches of the line and afterward the outer.

After the clothes are in place the cranks D' are turned to raise each pole. There will usually be only one operator, and the cranks may be turned one at a time.

10 The line W and its several stretches of the depending clothes (not shown) will for a brief period be in an inclined position; but when the cross-bars and their attachments are up to the proper level the parts may be secured 15 by fastening the gear-wheel D², and the whole will be in position for successful exposure of the clothing to the circulation of the air, and the drying will proceed in the ordinary manner.

20 To take off the clothes, the operation is reversed, the cranks being caused or allowed to turn in the proper direction, and the clothes are removed first from the outer and afterward from the inner stretches of the line. The 25 parts may be made light and graceful from metal either natural or variously surfaced. The cheaper forms of the invention may be made of hard wood.

Fig. 3 shows a lock-bar E extending across 30 engaging with the gear-wheel D² and also in corresponding notches b, formed in yoke B. When the pole and its attachments have been fully raised, this loose lock-bar E is dropped in place and locks the parts, so long as it is allowed to remain.

35 Modifications may be made without departing from the principle or sacrificing the advantages of the invention. The supports are adapted to stand on the ground or on a 40 flat roof of a building without any special construction, but there may be cases where it is practicable to permanently set posts of small diameter in the yard or on a roof and to mount the supports thereon by simply receiving such a permanently set post of metal 45 or hard wood in the hollow interior of the bottom of each post A, as shown in Fig. 6. In such case the introducing and removing of the radial bars A⁴ may be omitted.

50 Fig. 4 shows a modification in which a tube is substituted for the solid pole. In this form accurately-spaced holes are drilled. A

row of such holes constitute a series extending up and down in one side of the pole, the holes receiving the teeth of the operating 55 gear-wheel. For this use the teeth of the wheel should be cylindrical. They may be made by setting short pins in radial holes in an otherwise smooth wheel. In this form of 60 the invention I also show a similar series of holes in the opposite side of the pole and mount there another wheel with pins for teeth engaging in those holes. This construction allows wheels to serve usefully in holding the pole and its load against any twisting motion.

In Fig. 4, M* is the pole and M'* the series of holes which correspond to the teeth M' of the other form, the series of holes m* corresponding to the groove in the other form.

70 I claim as my invention—

1. Two upright tubular posts and means for supporting them, a pole movable up and down in the interior of each post carrying a cross-bar on the projecting upper end, fastenings on each cross-bar for a clothes-line arranged to hold such line in substantially parallel stretches between them, yokes B carrying shafts D with cranks D', and screws C adapted to perform the functions of holding 80 and liberating the yoke, and guarding the pole against being turned horizontally, all combined substantially as herein specified.

2. Two upright tubular posts A, a roller P near the top of each performing the two functions of relieving from friction and aiding to hold the inclosed parts against being turned horizontally, a pole movable endwise in each post, carrying a cross-bar at its upper end and having a longitudinal groove, and further provisions carried in the structure for engaging in such groove and insuring against horizontal revolving motion, and provisions by a shaft, gear-wheel and crank, for raising and lowering each bar and its attachments, all 90 combined and arranged to serve, substantially as herein specified.

95 Signed at South Norfolk, in the county of Norfolk and State of Virginia, this 15th day of April, A. D. 1905.

FRANK McMANUS.
